(57) **CLAIM**

The ornamental design for headband and speaker for communications headset, as shown and described.

DESCRIPTION

FIG. 1 is an upper front right perspective view of a headband and speaker for communications headset, the broken line drawings of a microphone boom of the communications headset in the drawings herein are for illustrative purposes only and form no part of the claimed design, the microphone boom of the communications headset being shown herein in an exemplary storage position for purposes of clarity.

FIG. 2 is a front elevational view of the headband and speaker of FIG. 1.

FIG. 3 is a rear elevational view of the headband and speaker of FIG. 1.

FIG. 4 is a left side elevational view of the headband and speaker of FIG. 1.

FIG. 5 is a right side elevational view of the headband and speaker of FIG. 1.

FIG. 6 is a top plan view of the headband and speaker of FIG. 1; and,

FIG. 7 is a bottom plan view of the headband and speaker of FIG. 1.
